US00D776699S

(12) **United States Design Patent** (10) **Patent No.:** **US D776,699 S**
Clymer (45) **Date of Patent:** **** Jan. 17, 2017**

(54) **DISPLAY SCREEN OR PORTION THEREOF
WITH GRAPHICAL USER INTERFACE**

(71) Applicant: **Lutron Electronics Co., Inc.**,
Coopersburg, PA (US)

(72) Inventor: **Erica L. Clymer**, Nazareth, PA (US)

(73) Assignee: **Lutron Electronics Co., Inc.**,
Coopersburg, PA (US)

(**) Term: **15 Years**

(21) Appl. No.: **29/542,356**

(22) Filed: **Oct. 13, 2015**

(51) LOC (10) Cl. **14-04**

(52) U.S. Cl.

USPC **D14/486**

(58) **Field of Classification Search**

USPC D14/485-495
CPC H04N 1/00424; G06Q 50/01; H04L 51/32;
